WIRING DEVICE

James B. Miller, Webster Groves, Mo., assignor to
 Mines Equipment Company, St. Louis, Mo., a
 corporation of Missouri

Application November 27, 1939, Serial No. 306,217

3 Claims. (Cl. 173—324)

This invention pertains to wiring devices which may be used for running temporary electric circuits. In many places, as for instance in mines, it is often desirable to run a temporary circuit for lighting or the like and to provide in such circuit a plurality of outlets or taps whereby current may be taken from the circuit for local purposes in the mine. The cables used in running such temporary circuits are subject to a great deal of rough treatment and it is desirable, therefore, to provide a very robust construction, particularly at the outlets.

One of the objects of this invention, therefore, is to provide such a wiring device and particularly an outlet whereby connection may be made to such a circuit which shall be simple to manufacture and which is capable of withstanding a great deal of abuse.

As such circuits are frequently changed from place to place, the flexible cables used therefor are subject to repeated bending. It has been found that where a plug socket outlet is connected into such a cable, the continual bending of the conductor wires causes the same to break at the point where soldered joints are made to the plug contacts.

Another object of this invention, therefore, is to provide a construction which will permit flexure of the conductors or cables without affecting any fixed or soldered joints.

Another object is to provide a construction for such an outlet connection whereby any tensile stress put upon the outlet portion by tension on the cables is taken up without subjecting the conductor wires to such stress.

Another object is to provide such a wiring device with hanger means whereby it may be secured to suitable supports by temporary or permanent fastenings.

Further objects will appear from the following description taken in connection with the accompanying drawing in which:

Figure 1 is a side view of a wiring device embodying this invention.

Figure 2 is a top view of the outlet portion as arranged before the flexible insulating housing or covering has been molded thereon.

Figure 3 is a top view of Figure 1 with part of the hanger shown in section.

Figure 4 is a side-view similar to Figure 1 but somewhat enlarged, with the insulating housing shown in section so as to illustrate the interior construction;

Figure 5 is a section on line 5—5 of Figure 4; and

Figure 6 is a sectional view of an end socket constructed in accordance with this invention.

The cables used for stringing temporary circuits of this kind are usually made up in continuous lengths with outlets at spaced intervals thereon so that current may be taken from the circuit at such outlets as for lighting purposes, or the like. These cables may be made up in any length and may be arranged for coupling one to another so as to extend the circuit for any desired distance.

Figure 1 shows a portion of such a cable at one of the outlets, which is indicated generally at 1. This may be constructed in the form of a plug socket which may have one or more sockets adapted to receive a connecting plug for making a temporary connection to the circuit. The embodiment selected for illustration in the drawing shows a two-conductor cable and the outlet 1 has two sockets, one connected to each of the conductors. These sockets may be arranged to receive the plug contacts 2 of any kind of current-consuming device, such as the lamp socket 3, or similar plug contacts arranged at the end of a second cable forming a branch circuit.

In the embodiment illustrated, plug sockets 4 of any suitable type provide contact elements for making connection to the branch circuit by receiving plugs such as 2. These may be of different sizes so as to be insertable at the sockets 4 in only one position in order to preserve a predetermined polarity in the branch circuit. In the embodiment illustrated, the sockets 4 are constructed of tubular members slotted longitudinally and laterally, as shown in Figure 4, so as to substantially cut away a section of the tube, thus rendering the latter flexible with respect to the tube, and this may then be resiliently compressed by a coil spring 5 slipped over the end of the slotted tube. The upper ends of the socket members 4 may be reduced in diameter, as shown in dotted lines in Figure 4, so as to provide a reduced neck about which the cable conductor may be looped as will now be described.

The main circuit cable 6 may be of the type having two flexible conductors 7 and 8 insulated from one another, and a pair of tension cords 9 and 10 running along the cable to take up the mechanical tension therein. These cords are usually of soft material and are laid alongside of the conductors 7 and 8, as shown in the end views in Figure 4, and the entire assembly covered with a rubber sheath 11.

In making the outlet 1, a portion of the sheath 11 is cut away for a proper length, as illustrated

in Figure 2, so as to expose the conductors 7 and 8 and the cords 9 and 10. In Figure 2 the cord 9 is shown cut away and the cord 10 is omitted entirely in order to more clearly illustrate the arrangement of the conductors 7 and 8. In the actual construction, however, these cords are not cut. In order to make connection between the conductors 7 and 8 and the sockets 4, each conductor is stripped of its insulation for a short length, as indicated at 12, and the bare portion is then looped around the socket member 4 at the reduced portion thereof. The loop is preferably executed by turning the conductor inwardly around the element 4 and then outwardly to continue along a cable. This places both ends of the loop on the outside, as shown in Figure 2. The opposite side, or middle, of the loop is then permanently connected to the element 4 by a fixed connection, such as the soldered joint indicated at 13. By fixed connection, as used in this specification and the appended claims, is meant such a connection as may be made by soldering, welding, or even clamping so as to render the two connected conductors immovable with respect to each other. It will be seen from Figure 2 that this method of connection provides an extended portion of the loop of the conductor between the fixed connection 13 and that portion of the conductor which continues along the cable. With this arrangement any flexure of the conductor 7 or 8, due to flexure of the cable 6, is taken up in this extended portion of the loop before reaching the fixed connection 13, and there will be practically no relative movement between the conductor 7 and the contact 4 at the connection 13. This is a great advantage as it eliminates the principal cause of failure by breakage of the conductor at the fixed connection. Accordingly, this device may be subjected to practically any amount of flexure without danger of breaking the conductors at the soldered joint.

The operation of looping the conductors around the contact elements 4 tends to shorten the cable 6 by the amount taken up in the loop. Since the cords 9 and 10 have not been cut this produces a slack portion in each conductor. This slack portion is then formed into a loop which is also looped about one of the contact elements 4. The loops of the cords 9 and 10, however, are placed around the elements 4 at points of larger diameter than the reduced necks about which the conductors 7 and 8 are looped. Accordingly, the loops in the conductors take up a slightly greater length of cord than is taken up in the conductors 7 and 8 by their loops. Accordingly there remains slightly greater slack in the conductors than in the cords and, consequently, any tension coming upon the finished device will be taken by the cords rather than by the conductors.

Figure 4 illustrates the manner in which the cords are looped about the contact elements. When the connections have been made as described, a housing or covering 14 of flexible insulating material, such as rubber, is molded about the entire assembly including the contact elements 4 and the looped portions of the conductors and the cords, leaving openings 15, of course, to permit the entry of the plugs 2 into the sockets 4.

In order to provide for adequately supporting the circuit at the outlet 1, a hanger 16 may be formed on the housing 14 during the molding operation. In order to strengthen this hanger, a web 17 of fabric is molded into the hanger 16. This may be placed as shown in Figure 5, being 70

doubled at that portion within the hanger 16 and the two layers separated and carried around the outside portion of the housing 14. The hanger 16 may be provided with a suitable opening 18 to receive a tie or other fastener for supporting the circuit. Auxiliary stiffening webs 19 may also be provided and these may be provided with fastener-receiving openings 20.

In the embodiment of Figure 6, the housing 14 is formed at the end of the cable 11 and the openings 15 and the elements 4 are positioned for insertion of the plug from the end of the housing.

It will be seen, therefore, that this invention 15 provides a construction for a wiring device of this character which is simple to make and which will provide a durable device in service. The arrangement of the loop in the conductor and the fixed connection 13 at the middle of the loop so 20 as to provide a substantial portion of the loop between that connection and the point where flexure usually comes upon the device is effective in preventing such flexure from being imposed upon the conductor at the fixed connection and accordingly ample flexibility is provided in that part of the conductor so that breakage due to such flexure is substantially eliminated. It will also be noted that the conductor is supported 25 interiorly of the loop by the rounded shank of the contact element at that portion of the conductor between the fixed connection and the beginning of the loop. This prevents any possibility of kinking and also insures a gradual flexure outwardly by unwinding the conductor progressively 30 from around the contact element. Accordingly, this arrangement insures the maintenance of a loop of substantial radius in which flexure is confined to those portions shaped from the fixed connection. The looping of the cords is so artfully arranged as to shorten them relatively to the conductors so that they are effective in taking up 35 tension put upon the cable 6 and in relieving the conductors of all stress due to such tension. The entire structure is then housed in a flexible rubber housing adapted to protect the parts and retain them in their proper relative positions while at the same time being capable of withstanding an unlimited amount of rough treatment without rendering the device inoperative. When the housing at the entry openings 15 is 40 formed, as illustrated in Figure 4, to match the end portions of the plug device 3, a water-tight joint may be made between these parts. The springs 5 may be so proportioned as to provide 45 a substantial pressure between the elements 4 and the plugs 2 so that the latter are securely held when once inserted. Accordingly, such a circuit may be allowed to lie on the ground, or to be temporarily suspended upon any sort of 50 structure and will be proof against injury or disarrangement even under rough handling.

While this invention has been described as embodied in a unitary device, it will be understood that individual features or sub-combinations 65 thereof may be useful by themselves without reference to other features or the complete combination. It is understood, therefore, that the employment of such individual features or sub-combinations is contemplated by this invention and within the scope of the appended claims. It is further obvious that various changes in the details of construction may be made within the scope of the appended claims without departing from the spirit of this invention, and it is to be

understood that the invention is not limited to the specific details shown or described.

Having thus described the invention, what is claimed is:

1. An electrical connector of the character described, comprising, a cable having a flexible conductor, a contact element connected to said conductor, a stripped portion of said conductor being looped entirely around said element at a rounded portion thereof and connected thereto by a fixed connection so as to leave a free portion of the loop supported interiorly by said rounded portion of said element, and means providing a flexible housing for said connected portion of said conductor and said element at said connection.

2. An electrical connector of the character described, comprising, a cable having a flexible conductor, a contact element connected to said conductor intermediate its ends, a stripped portion of said conductor being looped entirely around said element without being severed and connected thereto by a fixed connection at the middle part

5 of the loop only so as to leave the remaining portion of the loop relatively free for flexure, and means providing a flexible housing for said connected portion of said conductor and said element at said connection.

10 3. An electrical connector of the character described, comprising, a cable having a flexible conductor and a tension cord, a contact element connected to said conductor intermediate its ends, a stripped portion of said conductor being looped entirely around said element without being severed and connected thereto by a fixed connection at the middle part of the loop only so as to leave the remaining portion of the loop relatively free for flexure, and said cord also being looped entirely around said element so as to take up the slack produced by looping said conductor, and means providing a flexible housing for said connected portion of said conductor and said element at said connection.
